UNITED STATES PATENT OFFICE.

ROBERT H. MARRIOTT, OF BREMERTON, WASHINGTON.

RADIO RECEIVING SYSTEM.

1,407,205.

Specification of Letters Patent. Patented Feb. 21, 1922.

Application filed December 26, 1916. Serial No. 138,728.

To all whom it may concern:

Be it known that I, ROBERT H. MARRIOTT, a citizen of the United States, and resident of Bremerton, county of Kitsap, and State 5 of Washington, have invented certain new and useful Improvements in Radio Receiv- ing Systems, of which the following is a specification.

This invention relates to a method of and 10 apparatus for treating disturbing electric forces which have a capacity for producing violent, impulse or surge producing effects, so as to neutralize or cut out such effects before they reach instruments upon which 15 their action might be detrimental and to do this in such a way that other electric currents of a more sustained or periodic character will not be seriously interfered with in their transmission to and action upon the 20 same instruments.

It is the object of this invention to cause 25 the undesirable currents, the effects of which it is desired to dissipate or neutralize, to produce two currents of definite but differ- ent periods, then to transform one of these 30 currents into a current of the same period as the other and then, by combining these two currents after they have been made of the same period, cause both to be neutral- 35 ized, thus leaving only the effects produced by the periodic current which it is desired to transmit.

The features of novelty in my invention 40 will be hereinafter described and then specifically set forth in the claims.

In the accompanying drawings I have 45 shown diagrammatically certain constructions and arrangements of parts forming radio receiving systems in which my invention has been incorporated, the same repre- 50 senting the arrangements and combinations of parts which are well adapted for illus- trating the principles involved in my invention.

Figure 1 represents a system in which my 55 invention has been applied to a single antenna.

Figure 2 is a plan view of an antenna.

Figure 3 represents a system in which two 60 antennæ are employed, so connected with other parts that the objectionable effects pro- 65 duced in one circuit are counteracted by the like effects in the other.

Figure 4 is a double antenna system de- 70 signed for the neutralization of audio fre- 75 quency disturbances.

Figure 5 represents a method of neutral- 80 izing audio frequencies due to atmospherics set up in a radio receiver or amplifier.

Figure 6 is similar to Figure 5, but illus- 85 trating the use of a specific type of rectifier.

This invention is particularly well adapted 90 for use in radio signaling, to neutralize the disturbing effects produced by electric dis- charges or pulsations, such for instance as 95 are commonly referred to as "static," by interruptions produced in power currents, as by opening and closing switches, and by variations of any kind, whether produced accidentally or by design in electric currents 100 which may be capable of producing surges 105 or impulsive action on the receiving circuit, yet it is not limited to this particular field of use but is also applicable to the control of currents of much greater strength and 110 power, irrespective of the use to which they 115 may be applied. It may be applied to the control of power transmission lines and their protection against surges set up therein from any cause. I will more particularly 120 describe the application of my invention to radio telegraphy, as that is a field wherein it is at present more particularly applicable.

Referring to Figure 1, the device, repre- 125 sented as a whole by the character 1, repre- 130 sents an antenna and is of rectangular out- 135 line, consisting of an upper section 11, verti- 140 cal sections 12 and 14, and bottom section 13, the latter being shown as grounded. This also includes one coil 15 of a coupler 145 15, 16, through which the impulses are 160 transferred to the receiving or translating 165 mechanisms.

In the associated or receiving circuit 2 170 which contains the other coil 16 of the cou- 175 pler, 20 represents a detector 21 and 22 con- 180 densers, and 3, a translating mechanism, here 185 shown as a telephone.

Considering Figure 1, a direct discharge 190 of a disturbing or violently shocking char- 195 acter to the upper arm 11 of the antenna at point X flows in approximately equal quan- 200 tities in opposite directions producing mini- 205 mum excitation of the antenna circuit at the period to which the antenna and receiving 210 circuits are adjusted, thereby minimizing the 215 effect of the direct discharge to the antenna so far as concerns the receiving of radio mes- 220 sages sent on wave lengths corresponding to the period of said circuits.

The top wire 11 of the antenna circuit of 225 Figure 1 is indicated by the line 11 in Figure

2. Electromagnetic waves produced by more or less distant discharges in direction N or S from the antenna of Figure 2, tend to produce currents in opposite directions from 5 X through both branches 12 and 14 to earth, thereby minimizing the excitation of the antenna in the period to which it is adjusted for radio messages.

More or less distant discharges occurring in 10 the general direction W and E from the antenna 11 tend to produce more or less opposing currents in the antenna to earth but they also excite the antenna radio signal circuit 1, as shown in Figure 1, producing current of 15 the radio signal frequency to which it is adjusted. Up to this point disturbances from direct discharge, from distant discharges in directions N and S and a portion of those from direction W and E have been neutralized, still leaving at times an objectionable remainder in the form of radio frequency alternating current flowing in the antenna circuit at the period to which this circuit is adjusted.

25 The decrement of this remaining current is dependent on the constants of the antenna radio signal circuit, and is therefore more or less similar in radio frequency and decrement to the radio frequency and decrement 30 of the signals from a spark station. However, the irregular group frequency or spacing of the current trains due to the atmospheric discharges, differs from the nearly regular group frequency due to the spark 35 transmitters, or the note produced by beat receivers from constant amplitude transmitter signals. The radio transmitters and receivers produce regular frequencies which can be more or less tuned to, while the atmospherics produce effects that tend to shock a 40 resonant device, whatever be the period to which it is adjusted.

In times of more severe atmospherics the 45 neutralizing and diminishing of effects described above may not be sufficient but may require still further neutralization to assure practical radio receiving.

To neutralize the remaining effect of the 50 atmospheric discharges, a second similar antenna 10 of Figure 3 may be used, preferably in the same vertical plane as the first antenna, 1, and as indicated diagrammatically in Figure 3. The second antenna 10 is adjusted for one half the frequency or twice 55 the wave length of antenna 1. This second antenna operates like the first, leaving a residue in the form of current excited in it by the atmospherics at the period to which it is adjusted. However, this second antenna being 60 of half the frequency of the first, is too far out of tune to be materially affected by signals to which the first antenna is adjusted. By coupling the rectifying circuit 40, 45, 44 and 43, and circuit 40, 45, 46, 41 and 42 and 65 by coupling inductances 42 and 43 with in-

ductance 47, as diagrammatically shown in Figure 3, wherein rectifiers 41 and 44 cause the successive half waves to flow through inductance 42 and 43 in the same direction relative to 47, the frequency set up in 47 is 70 made to be twice the frequency of the current in antenna 10. The circuit which includes inductances 47, 48 and condenser 49, is adjusted for the same frequency as that produced in inductance 47 and is coupled 75 through the circuit which contains inductances 16 and 17 with antenna 1, so that the current induced in 48 from inductance 17 is of a like frequency and in opposite phase to that induced in 47 from 42 and 43. This 80 neutralizes the currents set up by atmospherics; however, as practically no current is set up in antenna 10 by the signal impulses to the frequency of which antenna 1 is tuned, there is practically no neutralizing 85 signal current set up in the circuit containing 47, 48 and 49, and the signal therefore affects detector 20 to render the signal audible in telephone receiver 23 through the usual functioning of detectors 20 and condenser 21.

A diagram to illustrate neutralization in the audio-frequency circuit is shown in Figure 4. In this two antennæ 1 and 10 as heretofore described are shown. Antenna 1 95 is coupled through inductances 15, 16 with circuit 5 which contains condenser 25, both these circuits being adjusted to the frequency of the radio signal, while antenna 10 and circuit 50 are adjusted to another frequency such that practically no current will be set up in them by a radio signal which acts upon antenna 1.

The circuits 240 and 241 which contain 105 detectors 200 and 201 in the two portions of the receiving system, are adjusted so that the audio frequency currents due to atmospherics and similar objectionable discharges, set up in the circuits containing condenser 27 and inductance 300 and that containing 28 110 and 29, are practically alike. 29 and 300 are opposing primaries coupled to the secondary 310 on the iron core 320.

The audio frequency currents due to the 115 atmospherics, produce neutralizing magnetic fields in secondary 310, while the radio signal currents due to the received radio signal, are practically only set up in antenna 1, so that the audio frequency currents due to the radio signal are set up in 120 circuit 27, 300, and transferred to the telephone receiver 23 without material neutralization.

This neutralizing in circuits subsequent 125 to the antenna circuit can be used in conjunction with other forms of antenna but, other things being equal, as much neutralization as is practicable in the antenna circuit is desirable because, if strong currents exist in the antenna, sufficient current is 130

frequently induced in the subsequent circuits to render rectifiers and detectors temporarily inoperative, or cause them to function in some unsatisfactory manner.

- 5 Where it is impractical to maintain two antenna for use in neutralization, circuits as schematically shown in Figure 5, may be used. In this, inductive windings, 6, 7 are connected to the radio receiver or amplifier 10 18, and adjusted to produce an approximately aperiodic circuit or a circuit having relatively the same shocking or impulse excitation effect on the audio frequency circuit 62 and 72. Circuit 62 is adjusted to the audio 15 frequency of the spark signal or the beat receiver note where constant amplitude radio signals are being received. Circuit 72 is adjusted to one half the frequency of circuit 62.

By means of the transformers 74, 75, 76 20 and 52, 53, 54, and 55, the frequency of the current induced in coil 55 is brought to twice that in circuit 72 and coil 74, and to the same frequency as that induced in winding 58 through the transformers 64, 65, 66 and 25 68, 69, 58.

Secondaries 55 and 58 are connected to bring the currents so induced into opposite phase in the circuit which contains the member 23, which is an amplifier, telephone receiver, or like instrument.

The shocking and irregular currents produced by atmospherics and by the improper operation of an amplifier, when used, produce practically an equal amount of effect in 35 circuits 72 and 62, which effect is neutralized as above described. While at the same time audio frequency currents due to the signal produce the chief effect in circuit 62, which circuit is tuned to that frequency. Any effect 40 of the signal which may be produced in circuit 72 is rectified and its frequency changed to twice that of the signal, which only neutralizes the signal current to a relatively small extent.

45 Figure 6 diagrammatically shows another arrangement of circuits for neutralization of the noise producing current due to atmospherics and amplifiers.

3 represents a receiver or amplifier. Circuits 30, 31, 32 and 33, 34, are adjusted so that with the receiver or amplifier 3 connected, they provide circuits having two principal degrees of freedom such that the maximum amount of current of one half 55 the audio frequency of the desired signal will flow through primaries 31 and 32, which latter inductances are adjusted in circuit for maximum current at one half the signal frequency, and so that the impulsive 60 irregular current due to atmospherics or undesirable functioning of the amplifier, will give practically equal energy effect in inductances 31 and 32 and produce current of

the signal frequency in inductance 33 and one half the signal frequency in inductances 65 31 and 32, or greater energy in 31 and 32 for elimination by dissipation or neutralization.

Windings 31 and 36 being on the same transformer core 35, and windings 32 and 70 37 on a similar core 38, and the cores being magnetized to the knee of the saturation curve by battery 8 through windings 80 and 81, the current induced in the suitably connected windings 36 and 37 is made to be 75 twice the frequency of the current in the windings 31 and 32 and the same as the frequency induced from winding 33 to 83. Windings 36, 37 and 83 are connected in the same circuit so that the currents produced 80 therein are in opposition, whereby the currents due to atmospherics and other shocking disturbances are neutralized, while the audio frequency currents produced by the signal are not materially neutralized. 85

The truth of the action above described is pointed out in the following publications: Institute of Radio Engineers, vol. 3, No. 1 of 1915, Papers on Radio Frequency Changers by Alfred N. Goldsmith; page 74. See 90 also German Patent No. 149761 to Epstein, of 1902, and also any available description of the radio frequency transformers used at the Sayville, Long Island radio station.

It is obvious that this principle of neutralization may be likewise carried out by forms of circuits, relative frequencies, methods of rectification, et cetera, other than these specifically described above and I do not limit myself to these particular illustrations and 100 explanations of the principle.

What I claim as my invention is:

1. In a radio signalling device, the combination with a plurality of receiving circuits susceptible to impulse excitation and 105 having radio frequencies, of a neutralizing circuit and a circuit which contains a stationary aperiodic frequency changer.

2. In a radio signalling device, the combination with a plurality of receiving circuits susceptible to impulse excitations and having radio frequencies, of a neutralizing circuit and means for coupling said first named circuits with said neutralizing circuit comprising two intermediate circuits, one 115 of which contains a stationary aperiodic frequency changer.

3. In a radio receiver, a plurality of aperiodic radio frequency circuits, a neutralizing circuit, coupled with said circuits, one 120 of said couplings including a stationary aperiodic frequency changer.

Signed at Seattle, Washington, this 16th day of December, 1916.

ROBERT H. MARRIOTT.
